UNITED STATES PATENT OFFICE

113,283

DESIGN FOR A RECEPTACLE FOR BATTERIES OR SIMILAR ARTICLES

Roland Reppert, Pelham Manor, N. Y., assignor to American Hard Rubber Company, New York,
N. Y.

Application May 18, 1938, Serial No. 77,262

Term of patent 7 years

To all whom it may concern:

Be it known that I, Roland Reppert, a citizen of the United States and a resident of Pelham Manor, in the county of Westchester and State of New York, have invented a new, original, and ornamental Design for a Receptacle for Batteries or Similar Articles, of which the following is a specification, reference being had to the accompanying drawing, forming a part thereof, and in which:

Fig I is a front elevation, and,

Fig. II is a side elevation of a receptacle for batteries or similar articles embodying my new design.

It will be understood that the ornamental characteristics of the sides of the receptacle not shown are substantially similar to those of the side illustrated in Fig. II, and that the top of the receptacle is conventional.

I claim:

The ornamental design for a receptacle for batteries or similar articles, as shown and described.

ROLAND REPPERT.
